No. 36,752.

Patented January 26, 1904.

UNITED STATES PATENT OFFICE.

CHARLIE A. POST, OF KANSAS CITY, MISSOURI.

DESIGN FOR A KITCHEN-CABINET.

SPECIFICATION forming part of Design No. 36,752, dated January 26, 1904.

Application filed October 19, 1903. Serial No. 177,707. Term of patent 7 years.

To all whom it may concern:

Be it known that I, CHARLIE A. POST, a citizen of the United States, residing at Kansas City, in the county of Jackson and State of Missouri, have invented a new, original, and ornamental Design for Kitchen-Cabinets, as illustrated in perspective by the accompanying drawing.

What I claim as new, and desire to secure by Letters Patent, is—

The ornamental design for a kitchen-cabinet as herein shown.

CHARLIE A. POST.
